(74) Attorney, Agent, or Firm—Diller, Ramik & Wight

(57) **CLAIM**

The ornamental design for a sign, as shown and described.

DESCRIPTION

FIG. 1 is a perspective view showing our new design, FIG. 2 is both a left and a right side elevational view, FIG. 3 is both a front and a rear elevational view, FIG. 4 is a top plan view; and, FIG. 5 is a bottom plan view. The vertical columnar elements are shown broken away to indicate indeterminate length.
